UNITED STATES PATENT OFFICE.

JAMES McF. LUCAS, OF PHILADELPHIA, PENNSYLVANIA.

DESIGN FOR AN INCENSE BURNER.

61,140.

Specification for Design. Patented June 27, 1922.

Application filed January 27, 1922. Serial No. 387. Term of patent 3½ years.

To all whom it may concern:

Be it known that I, JAMES McF. LUCAS, a citizen of the United States, residing in the city and county of Philadelphia and State of Pennsylvania, have invented a new, original, and ornamental Design for Incense Burners, of which the following is a specification, reference being had to the accompanying drawing, forming a part thereof.

Figure 1 is a perspective view of an incense burner embodying my invention.

Figure 2 is a top plan view.

I claim:

The ornamental design for an incense burner, as shown.

JAS. McF. LUCAS.
